UNITED STATES PATENT OFFICE.

JASPER C. ALEXANDER, OF FISHER'S STATION, INDIANA.

GATE.

SPECIFICATION forming part of Letters Patent No. 416,885, dated December 10, 1889.

Application filed May 13, 1889. Serial No. 310,560. (No model.)

To all whom it may concern:

Be it known that I, JASPER C. ALEXANDER, a citizen of the United States, residing at Fisher's Station, in the county of Hamilton and State of Indiana, have invented a new and useful Improvement in Swinging Gates, of which the following is a specification.

My invention relates to an improvement in swinging gates.

The object of my improvement is to provide means for nicely adjusting the width of the gate to the distance between the gate-posts, and for adjusting the position of the gate-latch so as to compensate for the racking of the gate-posts and the sagging or shrinking and swelling of the gate, all as hereinafter fully described.

The accompanying drawings illustrate my invention.

Figure 1 represents a side elevation showing the gate-posts plumb. Fig. 2 represents a side elevation of the opposite side, showing the gate-posts out of plumb and the gate adjusted to the new position of the posts. Fig. 3 represents, on a larger scale, a section of the gate at line $x x$, Fig. 1.

A and B are the gate-posts. The frame of the gate consists of the top and bottom rails C and D and side rail E (which are rigidly framed together and provided with a fixed brace F) and a side rail H, which is adjustably secured to the ends of the top and bottom rails by brackets $i i$ and j . Said brackets are rigidly attached at one end to the side rail H and extend along the top and bottom rails, and are secured thereto by bolts k and l , which pass through the rails and through slotted holes m in the brackets. Brackets $i i$ are secured to the outer and inner faces of

the side rail H and extend along the corresponding faces of the top rail C, so as to resist the side-thrust against the side rail, while bracket j is secured to the side rail in the angle formed by it with the top of the bottom rail D, and extends along the bottom rail, so as to prevent the side rail from dropping down. The gate-latch N is not permanently secured to the side rail, as is commonly the case, but is pivoted to a metallic casing O, which embraces the side rail H on three sides, and is adjustably secured thereto by a set-screw p , as shown in Fig. 3, the set-screw passing through the casing and impinging against the inner side of the rail. The gate is hinged on that side having the fixed side rail E to the post B in any suitable manner.

In operation the relation between the posts having from any cause been changed so as to widen or narrow the space between them, bolts k and l are loosened and rail H is adjusted so as to be parallel with and swing clear of post A. Bolts k and l are then tightened, and latch N is adjusted to engage the catch r on the post by releasing the set-screw p and moving casing O up or down, as may be required.

I claim as my invention—

In a gate, the frame having three sides rigidly secured together, the loose side rail H, the slotted brackets $i i$ and j , and bolts k and l , all combined and arranged to co-operate as specified, whereby the loose rail is adjustably secured to the frame, as and for the purpose specified.

JASPER C. ALEXANDER.
